Int. Cl. D21—01

U.S. Cl. D34—5

FIG. 1

FIG. 3

FIG. 1 is a top perspective view of a game board or the like showing my new design;

FIG. 2 is a side elevational view thereof; and

FIG. 3 is an end elevational view.

The characteristic feature of my design resides in the combination of checkerboard and triangular circle arrangement with the particular board configuration shown.

I claim:

The ornamental design for game board or the like, substantially as shown and described.
